UNITED STATES PATENT OFFICE.

ROBERT J. BELL, OF RICHMOND, VIRGINIA, ASSIGNOR TO ECONOMY BARREL CORPORATION, OF RICHMOND, VIRGINIA, A CORPORATION OF VIRGINIA.

BARREL CONSTRUCTION.

Application filed March 2, 1923. Serial No. 622,361.

To all whom it may concern:

Be it known that I, ROBERT J. BELL, a citizen of the United States, residing at Richmond, in the county of Henrico and 5 State of Virginia, have invented new and useful Improvements in Barrel Construction, of which the following is a specification.

This invention relates to a collapsible container, preferably made in the form of a barrel, the general object of the invention being to form the body of the barrel in sections and to make the top and bottom removable so that the parts can be packed 15 together and thus occupy but little space when shipping or storing the device.

Another object of the invention is to provide means whereby the sections of the body can be easily and quickly connected together 20 and the top and bottom can be fastened to the body.

This invention also consists in certain other features of construction and in the combination and arrangement of the several 25 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a perspective view of the improved barrel with its top removed.

Figure 2 is a perspective view of the two halves of the body of the barrel.

Figure 3 is a fragmentary sectional view showing the top in position.

Figure 4 is a transverse sectional view through one of the hook fasteners.

Figure 5 is a transverse sectional view through one of the teat form of fastener.

Figure 6 is a bottom plan view of the top.

Figure 7 is a perspective view of a modified form of top.

Figure 8 is a view showing how a number of the barrels can be placed together when in knocked down condition.

As shown in these views the body of the barrel is formed of the two halves 1 and 2, the barrel being preferably formed of metal which is provided with the ribs 3 55 to strengthen the same and the edges are

bent over, as shown at 4, to add strength to the construction. Hooks 5 are formed on one edge of each half and straps 5' are formed adjacent the other edge of each half for receiving the hooks to connect the two halves together. These straps are formed by cutting the metal and then pressing the portions between the cuts inwardly, as shown in the drawings. The hook carrying edge is offset, as shown at 6, so that the hooks 60 can properly engage the straps. Teats 7 are formed on the offset portion of each half adjacent the ends thereof and these teats are adapted to engage holes 8 in the abutting edge of the other half, these teats 65 and holes acting to hold the two halves together in addition to the hooks and straps. V-shaped projections 9 are formed adjacent the ends of the body by cutting the metal and pressing the portions between the cuts 70 outwardly, as shown. These projections are adapted to engage openings 10 formed in the top A and the bottom B of the barrel. After the parts are placed in position, wires 75 C are threaded through the projections for holding the top and bottom in place. The top and bottom are each provided with a reinforcing strip 11, preferably formed by bending over the outer edge of the flange and this reinforcing part is bent outwardly 80 at each opening, as shown at 12, to permit the projection 9 to pass.

The top and bottom may be provided with the ventilating holes 13 and the body may also be provided with such holes when 85 the device is to receive vegetables and the like which require ventilation. I may also form the top and bottom of two halves which are hinged together, as shown at 14 in Figure 7, so that the parts can be folded together when the barrel is knocked down.

By this arrangement it will be seen that the barrel can be easily and quickly knocked down and the two halves placed together with the top and bottom therein so that the barrel will occupy but little space when being shipped or stored. Figure 8 shows the parts of a number of barrels placed together for a shipment or storage. The parts can be fastened together in any suitable manner.

It is thought from the foregoing description that the advantages and novel features of my invention will be readily apparent.

I desire it to be understood that I may make changes in the construction and in the

combination and arrangement of the several parts, provided that such changes fall within the scope of the appended claims.

What I claim is:—

- 5 1. A barrel comprising a body formed of sections, hooks on one edge of each section, hook receiving parts on the abutting edge of the adjacent section, each part being formed by slitting the metal twice and 10 punching the part between the slits inwardly, teats on each section and holes in the sections for receiving the teats, end pieces for the barrel and means for detachably connecting them with the body.
- 15 2. A barrel formed of metal and comprising a body formed of two halves, hooks on

one edge of each half, hook receiving parts adjacent the other edge of each half, said parts being formed by slitting the metal and punching the part between the slit inwardly, teats on each half and the other half having holes for receiving the teats, a top and bottom, each having a flange fitting over the body, said flange having holes therein, projections formed on the body for 20 engaging the holes and flexible members adapted to be threaded through the projections and passing around the flanges.

In testimony whereof I affix my signature.

ROBERT J. BELL.
